Primary Examiner — Catherine A Tuttle*(74) Attorney, Agent, or Firm* — Morgan Lewis & Bockius LLP(57) **CLAIM**

I claim the ornamental design for a bottle, substantially as shown and described.

DESCRIPTION

FIG. 1 is a top, front and left isometric view of a bottle.

FIG. 2 is a front elevation view of FIG. 1.

FIG. 3 is a rear elevation view of FIG. 1.

FIG. 4 is a left side elevation view of FIG. 1.

FIG. 5 is a right side elevation view of FIG. 1.

FIG. 6 is a top plan view of FIG. 1; and,

FIG. 7 is a bottom plan view of FIG. 1.

The broken line in FIG. 7 defines the bounds of the claim within the bottom view. The broken lines illustrating the upper end and lower front portions of the bottle in FIGS. 1-6 are for illustrative purposes only. None of the broken lines form part of the claimed design.
